UNITED STATES PATENT OFFICE.

HARVEY C. WERTZ, OF HOMESTEAD, PENNSYLVANIA.

SCAFFOLD JACK.

Application filed February 20, 1922. Serial No. 537,824.

To all whom it may concern:

Be it known that I, HARVEY C. WERTZ, a citizen of the United States, residing at Homestead, in the county of Allegheny and 5 State of Pennsylvania, have invented certain new and useful Improvements in Scaffold Jacks, of which the following is a specification.

This invention relates to adjustable supporting jacks for scaffolds and has for an 10 object to provide a support for scaffolding that can be readily adjusted to support the scaffolding at different heights, which can be readily taken apart in taking down the scaffolding and readily assembled to receive a 15 supporting platform. A further object is to provide an adjustable scaffold supporting frame-work built up of triangular adjustable frames which can be adjustably joined together to form an adjustable platform supporting stand or which can be separately attached to a wall or roof to form 20 platform supporting brackets. Other objects will be apparent from the following 25 description in connection with the annexed drawings.

In said annexed drawings: Fig. 1 is an end elevation of a scaffold in which the improved jack is employed, showing the jack 30 in side elevation with portions broken away to show certain parts in section.

Fig. 2 is an end elevation of the scaffold showing in full lines the parts of the jack 35 fully telescoped and supporting the platform in lowermost position, and in dotted lines the jack extended and supporting the platform in an elevated position.

Fig. 3 is a perspective view of a pair of jacks set up and connected by bracing members ready to receive the platform.

Fig. 4 is a side elevation of the upper triangular frame of the jack, detached.

Fig. 5 is a side elevation of the lower triangular frame of the jack, detached.

Fig. 6 is a view showing in side elevation one of the adjustable triangular frames used as a part of a roof scaffold.

Fig. 7 is vertical sectional view showing in side elevation one of the triangular 50 frames attached to a vertical wall and forming part of a platform support.

Fig. 8 is a horizontal sectional view taken on line 8—8 of Fig. 7. Fig. 9 is a detail view showing in elevation the pivotal connection between the channel platform supporting member of the upper triangular frame and the adjustable brace together with the anchoring clevis carried by the pivot pin. 55

Fig. 10 is a detail view showing in elevation the pivotal connection between the adjustable brace bar of the upper frame and the channel side bar thereof together with the stop pin for holding the channel side bar of the upper frame in adjusted position 60 on the channel side bar of the lower frame. 65

Fig. 11 is a detail view showing in elevation the pivotal connection between the channel base bar and channel side bar of the lower frame. 70

Fig. 12 is a sectional detail view taken on line 12—12 of Fig. 1.

Fig. 13 is a sectional detail view taken on line 13—13 of Fig. 1. Fig. 14 is a sectional view corresponding to Fig. 12 showing a 75 modified construction of the side and brace bars.

Referring to the annexed drawings, the improved scaffold jack consists of two triangular frames adjustably and detachably 80 connected. The lower frame consists of a channel base bar 1, having its flanges 2 extending upwardly; a channel side bar 3, arranged with its channel facing inwardly; and pivoted at its lower end between the 85 flanges 2 of the base bar 1 on a pivot-pin 4 extending through the flanges 2 of the base bar; and an extensible brace bar connecting the free ends of the channel bars 1 and 3, consisting of a tubular bar 5 pivoted on a 90 transverse pivot-pin 6 between the flanges 2 of the bar 1 and a bar 7 which may be tubular or solid, pivotally connected between the flanges of the bar 3 by means of the pivot-pin 8. The bar 7 fits slidably within 95 the tubular bar 5 and has a series of centrally disposed apertures 9 adapted to register with similarly disposed apertures in the bar 5 and to receive a pin 10 to retain the bars in adjusted position. Pivotally 100 connected with the pin 6 outside the flanges 2 is a clevis 11 which is adapted to receive

an anchoring stake driven into the ground or may be used to anchor the frame to a vertical wall as will be hereinafter described. The base bar 1 has a series of nail holes 12 in the web thereof to enable the bar to be nailed to a floor, roof or wall.

The upper triangular frame consists of a channel base bar 13 arranged, when connected with the lower frame as shown in Fig. 1, 10 with its channel facing downwardly; a channel side rail 14 arranged with its channel facing outwardly and pivoted within the flanges of the channel bar 13 on a transverse pivot-pin 15; and a two part extensible brace 15 bar pivoted to the free ends of the channel bars and consisting of a tubular bar 16 pivoted between the flanges of the bar 13 on a transverse pin 17 and a bar 18 which may be tubular or solid, fits slidably within the 20 tubular bar 16 and is pivoted between lugs 19 suitably secured to the back of the channel bar 14. The bar 18 has a series of apertures 20 adapted to be brought into register with similar apertures in the bar 16 and to 25 receive a pin 21 to lock the bars in the desired adjusted position. The pivot-pin 17 at the inner end of the bar 13 carries a clevis 22 by means of which the upper end of the jack may be anchored to a wall. A portion 30 of the web of the bar 13 is cut away at the outer end thereof and the upper end 23 of the side bar 14 projects above the upper surface of the bar 13. At the inner end thereof, the bar 13 has a U-shaped brace rail receiving strap or stirrup 24 riveted to the web thereof. The strap 24 is adapted to receive a transverse brace rail 25 which extends across to a second supporting jack. Nail holes 26 are provided in the strap 24 40 whereby the brace rail 25 may be secured in place. Planks 27 are laid across the top of the rails 13 of two or more jacks and form the platform upon which the workmen stand. The planks 27 are prevented from 45 being accidentally pushed off the supporting jacks by the ends 23 of the bars 14 at the outer end of the bar 13 and by the brace rail receiving straps 24 at the inner end of the bar 13. To the inside of the side bar 14 50 of the upper frame immediately beneath the platform supporting bar 13 is attached a U-shaped rail receiving strap 28, similar to the strap 24 on the rail 13, adapted to receive a transverse brace rail 29 and provided with 55 nail holes 30 whereby the rail 29 may be secured against longitudinal movement therein.

As shown in Fig. 12 the channel side bar 14 of the upper frame is of a size to fit over the channel side bar 3 of the lower frame 60 and the side flanges thereof have short in-turned edge flanges 31 adapted to engage the outer edges of the flanges of the bar 3 and providing between them a slot for the bar 7 of the lower frame which is pivoted be-

tween the flanges of the channel bar 3. The 65 lower end of the channel bar 14 being open and the interior of the channel unobstructed, the bar 14 is adapted to be slipped upon the end of the bar 3 to adjustably unite the two triangular frames. The bar 3 is provided 70 with a series of apertures 32 adapted to receive a pin 33 upon which the lower end of the channel bar 14 rests and by means of which the upper frame may be supported at different elevations on the lower frame. 75 As indicated in Fig. 2 the platform supporting frame can be raised to the desired elevation with respect to the base frame and secured in such adjusted position by placing the pin 33 in the proper aperture in the bar 80 3 and the pins 10 and 21 in the proper apertures in the bars 9 and 18, respectively.

The adjustable brace bars of the two triangular frames provide means for independently adjusting the angle of the base 85 bar 1 and platform supporting bar 13 with respect to the diagonal telescopically connected bars 3 and 14. Thus if the scaffold is set up upon sloping or uneven ground the base bar 1 can be set on angle with respect to the horizontal corresponding to the slope of the ground and the separate jacks of the scaffold may have their bases sloping 90 at different angles.

To disconnect the two triangular frames 95 of the jack it is merely necessary to lift the upper frame until the channel side bar 14 of the upper frame slips off of the channel side bar 3 of the lower frame. As shown in Fig. 3, when the jacks have been set at the 100 desired height, diagonal brace bars 34, and 35, may be nailed to the brace rails 29 adjacent their ends, to each other at their crossing point and placed with their lower ends in the channels of the bars 1 to hold the 105 jacks against lateral movement.

As shown in Fig. 6 the base frame may be used as a jack for roof scaffolding. When so used, the bar 1 is nailed through the openings 12 in the web thereof to a 110 sloping roof 36 and the bar 7 is adjusted in the tubular bar 5 to bring the channel side bar 3 into horizontal position to support the planks 37 forming the platform.

As shown in Figs. 7 and 8 the lower frame 115 member may be secured to a vertical wall and serve as a platform supporting bracket. For this purpose the clevis 11 is slipped between a pair of weather boards and a key 38 inserted therethrough. The base bar 1 120 may be nailed to the wall through the openings 12 if desired. The bar 7 is telescoped into the tubular bar 5 and secured in a position in which the bar 5 extends at a right angle to the bar 1. When so positioned the side bar 3 becomes the brace bar and the platform planks 39 are placed upon the tubular bar 5. The end of the bar 3 projects 125

slightly above the bar 5 and forms a stop to prevent a plank 39 from slipping off the outer end of the supporting bar 5.

As shown in Fig. 14, the channel side bars 3 may be replaced by a pair of angle bars 3' arranged with their angles facing inwardly and fitting slidably over a T bar 14' replacing the channel side bar 14. The flanges of the angle bars 3' are retained in engagement 10 with the flanges of the T bar 14' by means of transverse pins 40 secured in the web of the bar 14'. The brace bar 7' is pivotally secured to the bars 3' by means of a transverse pin 8'.

15 What I claim, is:

1. A scaffold jack, comprising a pair of triangular supporting frames, each consisting of a base bar and a side bar of fixed length pivotally connected together at one 20 end and a two part telescopic brace pivotally connected to the free ends of the base and side bars, the brace bar of one of said triangular frames being formed to fit telescopically over the side bar of the other 25 triangular frame; means for securing said telescopically connected side bars in different adjusted positions; and means for securing the telescopic parts of said braces in different adjusted positions.

30 2. A scaffold jack, comprising a pair of reversely-related triangular frames, each frame having three sides pivotally connected and one of the sides adjustable to different lengths, and one of the side members of one 35 of said frames being telescopically and adjustably connected with a side member of the other of said frames.

3. A scaffold jack, comprising a pair of triangular frames one of the side members 40 of one of said frames being detachably, telescopically and adjustably connected with a side member of the other of said frames, each of said frames having a side member of 45 adjustable length connected with the telescoping portions of said telescopically connected side members.

4. A scaffold jack, comprising a pair of triangular frames, each consisting of a channel base member and a channel side bar 50 pivotally connected at their ends, and an extensible telescopic brace connecting their free ends, the channel side bar of one frame being of a size to fit telescopically over the channel side bar of the other frame; and means for securing said telescopically fitting channels in different adjusted positions.

5. A scaffold jack, comprising a base member; a platform supporting member; an extensible brace member extending diagonally 55 from one end of the base member to the opposite end of said platform supporting member; means for adjusting the angle between said base member and said diagonal member; and independent means for adjust-

ing the angle between said platform supporting member and said diagonal member. 65

6. A scaffold jack comprising a base member; a platform supporting member; a telescopic two part brace member extending diagonally from one end of the base member 70 to the opposite end of said platform supporting member; auxiliary brace members extending from said diagonal brace member to the base and platform supporting members respectively; and transverse brace securing 75 means carried by said platform supporting member and diagonal brace member, respectively.

7. A scaffold jack comprising a base member; a platform supporting member; an 80 extensible brace member extending diagonally from one end of the base member to the opposite end of said platform supporting member; and auxiliary adjustable members connected to said base member and platform supporting members, respectively and to said diagonal brace member. 85

8. A scaffold jack comprising a base member; a platform supporting member; an extensible brace member extending diagonally 90 from one end of said base member and projecting above said member; auxiliary adjustable brace members connected to said diagonal brace member and to said base member 95 and platform supporting members, respectively; and a transverse brace receiving member secured to the upper face of said platform supporting member on the end thereof opposite that to which said diagonal brace is connected. 100

9. In a scaffold jack, a triangular supporting frame comprising a channel base bar; brace bars pivotally connected within said channel at opposite ends of said base bar and pivotally connected to each other at their outer ends; one of said brace bars being made of two telescopic extensible parts; and an anchoring clevis pivotally attached to said channel base member at one end 105 thereof. 110

10. In a scaffold jack, a triangular supporting frame, comprising a channel base bar; and brace bars pivotally connected within said channel at opposite ends of said base bar and pivotally connected to each other at their outer ends, one of said brace bars being made in two telescopic parts having registering openings for locking devices, and said channel base bar having nail holes in the web thereof and a clevis pivotally connected to the end of one of said bars. 115 120

11. A scaffold jack, comprising a pair of triangular frames, each consisting of a base bar, a channel side bar and an extensible side bar said bars being pivotally connected at their ends, the channel side bar of one of said frames having its channel facing toward the inside of the frame and the 125

end of the extensible side bar of the frame connected within the channel; the channel side bar of the second frame having its channel facing outwardly and the extensible side bar of the frame connected to the back of said channel bar, said channel side bar of said second frame being adapted to telescopically receive the channel side bar of the first frame; and means for securing said

telescopically connected channel bars in different adjusted positions.

In testimony whereof I affix my signature in presence of two witnesses.
